CAR TRUCK

Walter H. Baselt, Chicago, Ill., assignor to American Steel Foundries, Chicago, Ill., a corporation of New Jersey

Application December 6, 1941, Serial No. 421,908

11 Claims. (Cl. 105—197.2)

My invention relates to railway car trucks and particularly to a design of railway freight car truck in common use comprising spaced side frames and a connecting bolster upon which the car body is normally supported. In such trucks the side frame structure is commonly of truss type with a tension member, a compression member, spaced columns defining a central bolster opening and window openings at opposite sides thereof, sometimes with the tension and compression members merging adjacent their ends with integral journal boxes and sometimes with other wheel connecting means such as pedestal jaws. In such forms of car trucks the most common practice is for the bolster ends to be spring mounted upon spring groups commonly positioned as a unit on a spring seat of the tension member at the bottom of the bolster opening. In assembling the car truck the usual practice is to enter the bolster end in the bolster opening at the bottom thereof and elevate the bolster into engagement with the column guide portions at the upper portion of the bolster opening, after which the spring group may be inserted on the spring seat beneath the bolster and the bolster lowered thereupon. Most railway freight car trucks in use at the present time follow such a method of assembly and for this reason the bottom of the bolster opening is made relatively wide in order to accommodate the guide lugs on the sides of the bolster and the upper portion of the bolster opening is made relatively narrow in order that the guide lugs on the bolster may engage guide portions on the columns.

The general object of my invention is to devise such a car truck as that above described wherein a plurality of spring means may be utilized at each spring seat more or less independently of each other and spring positioning means may be integrally formed with the side frame and bolster in order to obviate the necessity of otherwise securing the spring means.

As is well understood, the ordinary spring group consists of four to six outer coils and a varying number of inner coils and these may follow a variety of arrangements, but in most all instances the springs are confined between top and bottom spring plates in order to form a unit of the spring group and facilitate its handling as such. In such an arrangement a number of added parts necessarily are required which would not be needed if the springs were otherwise maintained in position after assembly.

Another object of my invention is to provide such means of maintaining various springs in

their proper assembled relationship on the spring seat without utilizing other guide means than those integrally formed with the side frame and bolster.

5 In such an arrangement as I propose it will readily be understood that relatively long positioning means may be required on both the side frame and the bolster as compared with those in normal use heretofore because no restraint will be placed upon the expansion of the various springs such as commonly occurs because of their confinement between top and bottom spring plates, but in order to utilize relatively long spring positioning means on the side frame and the bolster certain special features are required which are hereinafter set forth in detail.

A different object of my invention is to devise a novel form of freight car truck comprising a side frame, a bolster spring supported thereon 20 and normally projecting into a bolster opening of said side frame wherein the spring guide means on the side frame and bolster are arranged in alternate rows with the rows extending longitudinally of the bolster, that is, transversely of the truck.

A different object of my invention is to devise such a car truck as that just described comprising a side frame member and a load carrying member having opposed spring seats on one of which may be arranged a plurality of spring positioning means for each spring interposed therebetween and on the other of which may be arranged at least one positioning means for each spring interposed therebetween, and the spring 30 positioning means on the respective seats being alternately arranged with respect to each other to permit insertion of a bolster end of maximum depth in the normal bolster opening of the side frame.

40 Still another object of my invention is to devise an arrangement such as that just mentioned wherein certain of the positioning means on one of said spring seats may be adjacent to and serve to position a plurality of springs while, at the same time, all of said positioning means on the respective seats may be arranged in alternate rows transversely of the truck.

In the drawings,
50 Figure 1 is a fragmentary side elevation of a railway car truck embodying my invention.

Figure 2 is a fragmentary sectional view through the car truck shown in Figure 1, the section being taken substantially in the transverse vertical plane bisecting the truck as indicated by the line 2—2 of Figure 1.

Figure 3 is a further fragmentary sectional view, the section being taken substantially in the horizontal plane indicated by the line 3—3 of Figure 1.

Figure 4 is a fragmentary bottom plan view of the bolster end showing the spring seat thereon.

Figure 5 is a view comparable to Figure 2 showing an alternate arrangement of my novel form of car truck.

Figure 6 is a fragmentary sectional view of the truck arrangement shown in Figure 5 showing in plan a spring seat on the side frame, the section being taken approximately in the horizontal plane indicated by the line 6—6 of Figure 5.

Figure 7 is a fragmentary side elevation of a further modification of my invention, and Figure 8 is a plan view of the spring seat portions of the side frame and bolster, the side frame view being taken from the plane indicated by the line 8—8 of Figure 7 and the spring group and bolster superposed thereon.

Describing my novel arrangement in detail and referring first to the modification illustrated in Figures 1 to 4 inclusive, the general form of the side frame is well known comprising the compression member 2, the tension member 4, and spaced columns 6, 6 defining with said members the central bolster opening 8 into which may project the end of the bolster generally designated 9. Over the bolster opening the compression member 2 may have the box-section best illustrated in Figure 2 and similarly the tension member may be of box-section with the bottom chord 10, the top chord 12, the outboard and inboard walls 14 and 16. Beneath the bolster opening 8 the top chord 12 of the tension member may be widened to form the spring seat 17 and said widened portion may be reinforced by the spaced vertical ribs 18, 18 merging with said before-mentioned walls 14 and 16. Positioned upon the spring seat 17 may be the usual bolster supporting springs diagrammatically indicated at 19, 19.

In this well known form of truck the secondary truss extends through the lower portion of each column and merges with the spring seat of the tension member in a portion 20 which cuts across the lower corner of the bolster opening at each side thereof, the form and arrangement of the portion 20 being clearly apparent from a comparison of the views of Figures 1 and 3. The bolster opening 8 is also formed with a relatively wide portion extending upwardly from the spring seat of the tension member for approximately half the length of the column and thereabove the restricted width of the bolster opening affords a bolster guide portion 22 on each column with which may engage in the usual manner inboard and outboard guide lugs 24 and 26 on each side of the bolster. As illustrated in this modification, the side wall of the bolster between the guide lugs 24 and 26 is of convex form as may be seen at 28 (Figure 4) and the column engaging faces of the guide lugs 24 and 26 are diagonally arranged (Figure 4), the corresponding guide faces on the columns being complementary in shape with the concave configuration centrally thereof. The top of each outboard guide lug 26 on the bolster end may be formed on a smooth radius as indicated at 30 (Figure 1) to conform to the configuration of the radius at 32 on the column at the bottom of the guide portion 22 so that the bolster end may be entered into the bolster opening at the bottom thereof with convenient clearance of said lug from said guide portion 22.

Upstanding from the spring seat 17 of the side frame may be the symmetrically arranged spring positioning lugs 34, 34, the said lugs being arranged in spaced pairs with the lugs of each pair aligned transversely of the frame. The central portion of the spring seat 17 may be cored away in an opening at 36.

In Figure 4 is shown a bottom plan view of the end of the bolster 9 illustrating the spring seat portion thereof generally designated 38. Downwardly projecting from said spring seat 38 may be spring positioning means in the form of lugs arranged in rows longitudinally of the bolster 9, said lugs being so constructed and arranged as to permit the bolster end to be inserted through the widened portion at the bottom of the bolster opening 8 below the column guide portions 22, 22 at opposite sides of said bolster opening. In assembling or dismantling the bolster and side frame, the upstanding lugs 34, 34 on the frame are so positioned as not to interfere with the downwardly depending spring positioning lugs on the bolster, the lugs on the bolster, as already described, being arranged in rows between which the lugs on the side frame may pass as the bolster is entered into or removed from the bolster opening. By such an arrangement I am able to use upstanding lugs on the side frame and downwardly depending lugs on the bolster of maximum length and thus insure the proper positioning and secure maintenance against loss of the bolster supporting springs. Referring again to the downwardly depending lugs from the spring seat 38 on the bolster, it may be noted that at each side of the bolster end are formed a plurality of arcuate lugs 40, 40, two of which may be associated with each spring 19 and the lugs 40, 40 at each edge of the spring seat being arranged approximately in a line or row adjacent said edge. Intermediate arcuate lugs 42, 42, in shape similar to the lugs 40, may be formed on the spring seat in line with central lugs 44, 44, each of said central lugs having an arcuate configuration on opposite faces thereof for engagement with adjacent springs 19, 19 and said lugs 42 and 44 being arranged in two rows adjacent the longitudinal center line of the bolster and spaced from the two rows of lugs 40, 40 to accommodate the springs 19, 19 which may be positioned therebetween. It will thus be seen that a row of arcuate lugs 40, 40 is formed adjacent each edge of the bolster and intermediate rows parallel to the first-mentioned rows are formed by the lugs 42 and 44 with the lugs 44, 44 affording positioning means not only for the central spring 19 but also for an adjacent spring with all of the lugs 40, 42, and 44 arranged in rows longitudinally of the bolster. The bolster may be entered into or disengaged from the bolster opening of the side frame without interfering with the upstanding lugs 34, 34 on the spring seat of the side frame, the said spring seat lugs 34, 34 normally passing between the rows of lugs on the bolster and thus permitting the use of relatively long lugs on both the load carrying member and the side frame member of the truck while, at the same time, having a bolster opening of normal height and width as well as a bolster end of normal depth. It will be observed that by my novel arrangement I may utilize spring positioning means in a variety of arrangements, it being always understood that the lugs on the side frame must be arranged in rows which may pass between the rows of lugs on the bolster which may also be arranged in rows transversely of the truck. By this means I am able to afford satisfactory posi-

tioning means for the bolster supporting springs of such size as to insure their remaining securely in position without the use of spring plates between which the springs would otherwise necessarily be confined against loss.

In the modification illustrated in Figures 5 and 6, the arrangement of spring positioning lugs on the side frame and bolster is substantially the converse of that described for the modification illustrated in Figures 1 to 4 inclusive, Figures 5 and 6 showing the lugs up standing from the side frame positioned around the circumference of the spring and the lugs depending from the bolster centrally of the spring. In this modification the side frame structure is identical with that just described comprising the compression member 102 and the tension member 104 with the spring seat 106 below the bolster opening 108 into which may project the bolster 110, said bolster having a spring seat 112 from which may depend the spring positioning means 114, 114, said spring positioning means being arranged in two rows each row comprising a pair of lugs 114. On the spring seat 106 of the side frame may be positioned the springs diagrammatically indicated at 116, 116, said springs being arranged similarly to those of the previous modification as shown in the plan view of Figure 6. The up-standing spring positioning lugs on the side frame comprise the lateral rows of arcuate lugs 118, 118 adjacent the columns 119, 119, two adjacent lugs serving as positioning means for a single spring 116. Other positioning means on the spring seat 106 are arranged in two rows adjacent the transverse center line of the frame and include arcuate lugs 120, 120 adjacent the inboard and outboard edges of the spring seat as well as the central lugs 122, 122 which have a concave configuration on opposite faces thereof to afford positioning means for adjacent springs, one of which in each case consists of the center spring. In this arrangement also the intermediate lugs 120 and 122 are positioned in two spaced rows conveniently spaced from the rows of lugs 118, 118 to accommodate the springs 116, 116 and at the same time to permit the lugs 114, 114 of the bolster to pass between adjacent rows of lugs on the side frame in assembling or dismantling the bolster at the bottom of the bolster opening 108, the configuration of the bolster opening in this modification being identical to that of the previous modification with similar side frames and bolster.

In the further modification illustrated in Figures 7 and 8 I have illustrated a similar side frame structure comprising a compression member 202, a tension member 204, the spaced columns 206, 206 merging therewith to form the bolster opening 208, said bolster opening having the same configuration as that described for the previous modifications with each column having adjacent the upper end thereof the bolster guide portion 210 for engagement with inboard and outboard guide lugs 212 and 214 formed on the side walls of the bolster 216. In this modification I have utilized a greater number of spring positioning lugs on both the side frame and the bolster for a spring group identical to that described for the previous modifications and including a plurality of springs 211, 211, the depending spring positioning lugs from the spring seat 218 of the bolster being arranged in three rows, one adjacent each side thereof and one along the longitudinal center line of

the bolster, while the lugs upstanding from the spring seat 220 of the side frame are arranged in four rows transversely of the truck, two rows adjacent the respective columns 206, 206, and two intermediate rows, said intermediate rows being alternately positioned with respect to the before-mentioned rows on the bolster with which they must interlace in the operation of assembling or dismantling the truck parts. In the modification at present under consideration, the lugs on the side frame seat adjacent the columns thereof are designated 222, 222. Each intermediate row of lugs on the side frame comprises a lug 224 adjacent the outboard edge of the spring seat, an inboard lug 226 adjacent the inboard edge of the spring seat, and two intermediate lugs 228, 228 each having opposed concave faces affording positioning means for adjacent springs, one of which is the center spring.

The downwardly depending lugs on the bolster are arranged in three rows as aforesaid, the row at each side of the bolster comprising an outboard lug 230, an inboard lug 232, and spaced intermediate lugs 234, 234, while the middle row on the bolster arranged along the longitudinal center line thereof comprises spaced lugs 236, 236 each of which may present at opposite sides thereof concave faces affording positioning means for adjacent springs. In this arrangement it will be observed that the rows of lugs on the side frame alternate with the rows of lugs on the bolster and the manner in which these interlace with each other is well illustrated in Figure 7 where I have shown in dotted lines at the bottom of the bolster opening 208 the bolster in its entering position designated 216A. In the position 216A it will be observed that the guide lugs 214A at opposite sides of the bolster conveniently clear the lower edges of the columns 210, 210 as indicated at 238, 238 when the bolster lugs 230A are in position to clear the secondary truss portion 240 of the side frame which cuts off each bottom corner of the bolster opening.

Looking at Figure 8 it will be noted the four rows of lugs on the side frame alternately arranged with the three rows of lugs on the bolster are made up as follows, reading left to right: side frame row comprising lugs 222, 222, bolster row comprising lugs 230, 232, and 234, side frame row comprising lugs 224, 226, and 228, bolster row comprising lugs 236, 236, side frame row including lugs 224, 226, and 228, bolster row comprising lugs 230, 232, and 234, side frame row comprising lugs 222, 222.

While this lug arrangement is distinct from that illustrated in the two preceding modifications which are the converse of each other, nevertheless all modifications are alike in showing rows of lugs so positioned on the spring seats of the side frame and bolster as to permit their interlacing with each other when the parts are assembled or dismantled, thus accommodating spring positioning means of maximum length on the opposed spring seats.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a railway car truck, a side frame comprising tension and compression members and spaced columns defining a bolster opening, said opening having a relatively wide lower portion and a relatively narrow upper portion defined by bolster guide faces on said columns, a bolster projecting into said opening, springs on said tension member supporting said bolster, and spring positioning means fixed on said tension member and said bolster, said spring positioning means being arranged in rows transversely of said truck to accommodate the interlacing thereof when said bolster is assembled or dismantled at the bottom of said bolster opening, said spring positioning means on said bolster comprising side rows and intermediate rows of lugs, certain of said intermediate lugs affording support for a plurality of springs.

2. In a railway car truck, a side frame comprising tension and compression members and spaced columns defining a bolster opening, said opening having a relatively wide lower portion and a relatively narrow upper portion defined by bolster guide faces on said columns, a bolster projecting into said opening, springs on said tension member supporting said bolster, and spring positioning means fixed on said tension member and said bolster, said spring positioning means being arranged in rows transversely of said truck to accommodate the interlacing thereof when said bolster is assembled or dismantled at the bottom of said bolster opening, said spring positioning means on said side frame comprising side rows and intermediate rows of lugs, certain of said intermediate lugs affording support for a plurality of springs.

3. In a railway car truck, a side frame comprising tension and compression members and spaced columns defining a bolster opening, said opening having a relatively wide lower portion and a relatively narrow upper portion defined by bolster guide faces on said columns, a bolster projecting into said opening, springs on said tension member supporting said bolster, and spring positioning means integrally formed on said tension member and said bolster, said spring positioning means being arranged in rows transversely of said truck to accommodate the interlacing thereof when said bolster is assembled or dismantled at the bottom of said bolster opening, said spring positioning means on said bolster comprising a plurality of rows, certain of said rows including lugs affording support for a plurality of springs.

4. In a railway car truck, a side frame comprising tension and compression members and spaced columns defining a bolster opening, said opening having a relatively wide lower portion and a relatively narrow upper portion defined by bolster guide faces on said columns, a bolster projecting into said opening, springs on said tension member supporting said bolster, and spring positioning means fixed on said tension member and said bolster, said spring positioning means being arranged in rows transversely of said truck to accommodate the interlacing thereof when said bolster is assembled or dismantled at the bottom of said bolster opening, said spring positioning means on said side frame comprising a plurality of rows, certain of said rows including lugs affording support for a plurality of springs.

5. In a railway car truck, a side frame comprising tension and compression members and spaced columns defining a bolster opening, said

opening having a relatively wide lower portion and a relatively narrow upper portion defined by bolster guide faces on said columns, a bolster projecting into said opening, springs on said

5 tension member supporting said bolster, and spring positioning means fixed on said tension member and said bolster, said spring positioning means being arranged in rows transversely of said truck to accommodate the interlacing thereof when said bolster is assembled or dismantled at the bottom of said bolster opening whereby spring positioning means of maximum length may be utilized on said bolster and said side frame in a bolster opening of normal depth.

15 6. In a railway car truck, a truss side frame having a tension member, a compression member, and spaced columns defining a bolster opening, a bolster in said opening, opposed spring seats on said side frame and bolster, springs there-

20 between, and spring positioning means on said spring seats arranged in rows transversely of said truck, the rows on each spring seat comprising lateral rows and intermediate rows and the rows on the side frame seat being alternately arranged

25 with respect to the rows on the bolster seat to permit interlacing thereof when said bolster is inserted into said bolster opening at the bottom thereof, certain of the lugs of said intermediate rows affording positioning means for a plurality of adjacent springs.

7. In a railway car truck, a side frame comprising tension and compression members and spaced columns defining a bolster opening, said opening having a relatively wide lower portion

35 and a relatively narrow upper portion defined by bolster guide faces on said columns, a bolster projecting into said opening, springs on said tension member supporting said bolster, and spring positioning means on said tension member and

40 said bolster projecting toward each other, said spring positioning means comprising alternately arranged rows on said side frame and said bolster preventing interference thereof and affording maximum length therefor while permitting assembling or dismantling of said bolster at the bottom of said bolster opening.

8. In a railway car truck, a truss side frame having a tension member, a compression member, and spaced columns defining a bolster opening, a

50 bolster therein, opposed spring seats on said side frame and bolster, springs therebetween, and spring positioning means fixed on said spring seats arranged in rows transversely of said truck, the rows on each spring seat comprising lateral

55 rows and intermediate rows and the rows on the side frame seat being alternately arranged with respect to the rows on the bolster seat to permit interlacing thereof when said bolster is inserted into said bolster opening at the bottom thereof.

60 9. In a railway car truck, a truss side frame having a tension member, a compression member, and spaced columns defining a bolster opening, a bolster therein, opposed spring seats on said side frame and bolster, springs therebetween, and spring positioning means on said spring seats

65 arranged in rows transversely of said truck and projecting toward each other, the rows on each spring seat comprising lateral rows and intermediate rows of lugs, certain of the lugs of said intermediate rows affording positioning means for a plurality of adjacent springs, and the rows on the respective seats being so arranged as to avoid interference with each other while in overlapping relationship as said bolster is assembled

or dismantled at the bottom of said bolster opening.

10. In a railway car truck, a truss side frame having a tension member, a compression member, and spaced columns defining a bolster opening, a bolster therein, opposed spring seats on said side frame and bolster, springs therebetween, and spring positioning means on respective spring seats arranged in rows transversely of said truck and projecting toward each other, the rows on each spring seat comprising lateral rows and intermediate rows, said rows being so constructed and arranged on said respective seats as to permit their vertical overlapping when said bolster is positioned at the bottom of said opening without interfering with lateral movement of said bolster with respect to said side frame in its application or removal therefrom.

11. In a railway car truck, a side frame having tension and compression members and columns defining a bolster opening, said opening having a relatively wide lower portion, a bolster projecting into said opening, said bolster having an end for cooperative engagement with said side frame columns, said end being insertable in said relatively wide portion of said opening and dismountable therethrough, opposed spring seats on said tension member and said bolster, and rows of positioning means on respective spring seats projecting toward each other and alternately arranged to avoid interference thereof in said assembling or dismantling.

15

WALTER H. BASELT.
